(57) **CLAIM**

The ornamental design for an in-wall iPad dock, as shown and described.

DESCRIPTION

FIG. 1 is a front elevational view of an in-wall iPad dock showing the new design;

FIG. 2 is a right side elevational view thereof, the left side being a mirror image of the right side; and,

FIG. 3 is a top plan view thereof, the bottom being a mirror image of the top.

The portions of the dock shown in broken lines form no part of the claimed design.

1 Claim, 3 Drawing Sheets

FIG. 1

FIG. 2

FIG. 3
